HIS ATTORNEY.

UNITED STATES PATENT OFFICE

158,118

PORTABLE SITZ BATH

Sheffield F. Oliver, Auburn, Calif.

Application July 29, 1947, Serial No. 140,581

Term of patent 14 years

(Cl. D4—4)

To all whom it may concern:

Be it known that I, Sheffield F. Oliver, a citizen of the United States of America, residing in the city of Auburn, county of Placer, and State of California, have invented a new, original, and ornamental Design for a Portable Sitz Bath, of which the following is a specification; reference being had to the accompanying drawing, forming part thereof.

Fig. 1 is a plan view of a portable sitz bath, showing my new design;

Fig. 2 is a front elevation; and

Fig. 3 is a side elevation.

I claim:

The ornamental design for a portable sitz bath, as shown.

SHEFFIELD F. OLIVER.
